(57) **CLAIM**

The ornamental design for a folding step ramp, as shown and described.

DESCRIPTION

FIG. 1 is a perspective view of the folding step ramp, showing the new design;

FIG. 2 is an alternate perspective view of the folding step ramp thereof;

FIG. 3 is a front elevational view of the folding step ramp thereof;

FIG. 4 is a rear elevational view of the folding step ramp thereof;

FIG. 5 is a left side elevational view of the folding step ramp thereof;

FIG. 6 is a right side elevational view of the folding step ramp thereof;

FIG. 7 is a top plan view of the folding step ramp; and,

FIG. 8 is a bottom plan view of the folding step ramp thereof.

1 Claim, 5 Drawing Sheets
